UNITED STATES PATENT OFFICE.

JAMES SAMUEL JONES, OF HARRISON, ARKANSAS.

SYRUP-PITCHER.

1,130,738.

Specification of Letters Patent.

Patented Mar. 9, 1915.

Application filed December 27, 1913. Serial No. 809,069.

To all whom it may concern:

Be it known that I, JAMES S. JONES, a citizen of the United States, residing at Harrison, in the county of Boone and State 5 of Arkansas, have invented a new and useful Syrup-Pitcher, of which the following is a specification.

The present invention appertains to syrup pitchers, and aims primarily to provide a 10 novel and improved receptacle or container of that character.

It is the object of the present invention to provide a syrup pitcher comprising a 15 unique assemblage of parts, the several parts being readily manufactured and assembled, whereby the construction of the pitcher will be comparatively simple, compact and inexpensive, and whereby the pitcher will be 20 convenient, practical and efficient in its use.

A further object of the present invention is to provide unique means for attaching the 25 cap to the neck or pouring spout of the pitcher.

A still further object of the present invention is to provide a novel assemblage 30 of the component parts, whereby a drip chamber will be provided for receiving the drippings, and for returning them to the body of the pitcher, or the receptacle or container proper.

It is also within the spirit of the present invention to provide such an assemblage of component parts, whereby the several parts 35 may be readily separated for the purpose of cleaning, repair or replacement.

With the foregoing and other objects in view, which will be apparent as the nature of the invention is better understood, the present invention resides in the combination 40 and arrangement of parts and in the details of construction hereinafter described and claimed, it being understood that changes in the precise embodiment of the invention herein disclosed, can be made 45 within the scope of what is claimed, without departing from the spirit of the invention.

The invention has been illustrated in its 50 preferred embodiments in the accompanying drawing, wherein:—

Figure 1 is a longitudinal or vertical section of one form of the improved syrup pitcher. Fig. 2 is a similar view of a second form. Fig. 3 is a rear elevation of the 55 stopper illustrated in Fig. 2. Fig. 4 is a per-

spective view of the cap attaching clip. Fig. 5 is a view similar to Figs. 1 and 2, of a third modification or variation, parts being broken away.

Referring specifically to the form of the 60 invention illustrated in Fig. 1, the same embodies a metallic receptacle or container 1, which is preferably spun from aluminum, although it may be fashioned from other sheet metals. The receptacle 1 is tapered from its upper end or mouth to its lower end, and is preferably provided with a relatively large roll or bead 2 about its mouth or at its upper end.

A base 3 is provided for the receptacle 1, and is also preferably spun from aluminum, although it may be fashioned from other suitable stock. The base 3 embodies an upright collar or sleeve 4 snugly receiving the 65 lower end portion of the receptacle 1, and having a lower flared flange 5 formed around its edge with a bead 6 to rest on a table or other surface. The collar or band 4 of the base and the lower end portion of the receptacle 1 are provided with interfitting or interlocking peripheral corrugations 7, these corrugations being readily formed by applying the receptacle and base to a suitable lathe, and impressing the corrugations by suitable tools or implements, according 70 to the usual "spinning" method.

A handle 8 is provided, the same having 75 its upper end secured to the upper end portion of the receptacle 1, by means of a rivet 9 disposed adjoining the mouth of the receptacle, or the bead 2 surrounding the mouth. The lower end of the handle 8 is secured, by means of a rivet 10, to the upper edge portion of the collar or band 4 of the base, above the corrugations 7, the inner 80 head of the rivet 10 being preferably countersunk, so as to rest or fit snugly between the wall of the receptacle 1 and the collar or band 4. The rivet 10 does not puncture or penetrate the receptacle 1, which is especially desirable when aluminum is employed, inasmuch as aluminum is more or less pliable or malleable and does not give a good 85 hold for rivets. The rivet 10 in working loose, therefore, could not cause the receptacle 1 to spring a leak, which might result if the said rivet extended through the wall of the receptacle. The rivet 9 being disposed at the mouth of the receptacle, would 90 not cause the receptacle to spring a leak,

should the rivet 9 work loose, inasmuch as the receptacle 1 would not be filled up to the level of the rivet 9.

The base 3 and receptacle 1 are not only fashioned in a simple and efficient manner, for permitting the receptacle 1 to be readily supported upon a table or other object, but the base also serves as a means for anchoring the lower end of the handle 8 thereto, without weakening the receptacle 1. The base 3 will be more or less ornamental or neat in appearance, and will be substantial, as well as preventing the receptacle 1 being readily toppled or tipped over.

The stopper 11 is also preferably spun from aluminum, but may be otherwise fashioned, and embodies the neck or spout portion 12, and the lower enlarged and tapered portion 13 forming the shoulder 14. The enlarged and tapered portion 13 is adapted to fit snugly within the receptacle 1 directly below the mouth or upper end of the receptacle, whereby a drip chamber is formed above the shoulder 14 between the rim of the receptacle 1 and the neck or spout portion 12 of the stopper. The upper end of the neck or spout 12 is provided with an inturned flange 15, the opening formed by the flange 15 being preferably eccentric relative to the neck or spout 12, whereby the flange or lip 15 will be relatively narrow at that side of the neck or spout opposite the handle 8, to facilitate the ready decanting or pouring of the contents of the receptacle 1 when the same is tilted. The shoulder 14 is provided with an opening or slot 16 at that side adjoining the handle 8, and which opening or slot preferably extends slightly into the enlarged and tapered portion proper, and into the lower end portion of the neck or spout 12. The opening or aperture 16 leads from the drip chamber to the interior of the receptacle.

A primary cap or cover 17 is provided for the upper end of the neck or spout 12, and is pivotally connected to the said neck or spout by means of a clip 18. This clip, which is preferably fashioned from sheet aluminum, as well as the cap 17, embodies a body or strip 19 having the flexible tongue 20 projecting from one end, and having the angular flexible tongue 21 at its other end. The body or strip 19 of the clip is provided with laterally projecting arms 22 at its upper end, or adjoining the upper tongue 21, which arms have the apertured angular ears 23 at their free or outer ends. The body or strip 19 is further provided with laterally projecting arms 24 below the arms 22, which arms 24 have the angular ears 25 at their free ends. The ears 23 and 25 of the arms 22 and 24, respectively, project in opposite directions, or project outwardly and inwardly respectively. In applying the clip 18 to the stopper, the lower or free end of

the depending or lower tongue 20 is inserted through the opening 16 in the shoulder 14 of the stopper and bent upwardly, and the upper tongue 21 is bent back over the flange or lip 15 of the stopper neck or spout. The body portion of the clip rests snugly against the outer side of the stopper above the lateral opening 16. The free ends of the tongues are bent back within the spout and project toward each other and rest against the corresponding portion of the stopper or spout, as clearly indicated in Fig. 1, to lock the clip in place. The cap or lid 17 is provided with a suitable thumb piece 26 having the downturned ears 27 at its side edges and overlapping the ears 23 of the clips, a pivot pin 28 being passed through the ears 23 and 27 to pivot the cap 17 to the clip. A coiled wire torsional spring 29 is disposed on the pivot pin 28 between the two pairs of ears 23-27, and has its terminals or ends engaging the cap 17 and one of the arms 22, respectively, to yieldingly close the cap 17, the periphery of the said cap being seatable upon the flange or lip 15 of the neck or spout 12. The ears 25 of the arms 24 are adapted to engage the neck or spout 12 at the sides of the tongue 20 and strip or body 19 to prevent the clip from swinging about its longitudinal axis. In this manner, the cap 17 is readily attached to the stopper, whereby the stopper will be normally closed.

A supplemental or auxiliary cap or hood 30 is provided, the same having its edge or rim enlarged or flared, as at 31, to fit over the rim or bead 2 of the receptacle 1, whereby the outer or auxiliary cap 30 will inclose the stopper as well as the drip chamber formed thereby.

When the stopper is applied within the receptacle 1, the enlarged and tapered portion 13 thereof is adapted to fit snugly within the receptacle below the rivet 9, whereby the rivet will be located within the drip chamber, to guard against leakage, should the rivet 9 become loose. When the receptacle 1 is filled with syrup or any other liquid or semi-liquid, the contents may be readily decanted or poured therefrom, by first removing the outer cap 30, and then opening the cap 17 by pressing the thumb piece 26 downwardly, or toward the handle 8. The handle 8 may be readily grasped in the hand so that the thumb may be employed for opening the cap 17. By tilting the receptacle 1, the contents thereof may be readily poured through the neck or spout 12. Any drippings running over the sides of the neck or spout 12 will flow into the drip chamber or upon the shoulder 14, and will be constrained to run or flow along the said shoulder to the opening 16, and will then flow back into the receptacle 1.

The present pitcher will be sanitary in use, the several parts thereof being readily

separated for purpose of cleaning, or for the purpose of replacing broken or injured parts. By removing the cap 30 and stopper 11 from the receptacle 1, the receptacle 5 1 may be employed as an ordinary pitcher or tumbler.

Referring to Fig. 2, wherein a second variation of the invention is depicted, there is illustrated a glass receptacle or tumbler 1' having the handle 8' at one side. The stopper 11' is also fashioned from glass, and includes the neck or spout 12' and the lower enlarged and tapered portion 13' to fit within the receptacle 1' below the rim 15 or mouth thereof. The contacting portions of the receptacle 1' and the enlarged and tapered portion 13' of the stopper are preferably frosted whereby the stopper may efficiently grip the receptacle 1' to hold the stopper in place. The shoulder 14' formed by the enlarged portion 13' is provided with an opening 16' in that side adjoining the handle 8', for directing the drippings back into the receptacle 1', similar 20 to the form above described. The cap 17, clip 18, and outer or supplemental cap 30 are the same as those above described, and need not be again described in detail. It is evident that the lower or depending 25 tongue 20 of the clip may be readily engaged through the opening 16' to be bent back upon the interior of the neck or spout 12', while the upper tongue 21 may be readily seated upon and bent within the 30 rim or upper end of the neck or spout 12', to lock the clip in place. The periphery of the cap 17 is seatable upon the upper end of the neck or spout 12', while the outer or auxiliary cap 30 is adapted to be 35 slipped over the rim or upper end of the receptacle 1'.

With the glass stopper 11', it is preferable to provide the spout or neck 12' with a flattened portion 32 against which the 40 body or strip 19 of the clip 18 is adapted to rest, and forming side shoulders 33 over which the ears 25 of the arms 24 may engage, to lock the clip in place in a most effective manner.

50 With the exceptions noted, the general

structure disclosed in Fig. 2, is similar to that disclosed in Fig. 1, and the advantages are practically the same.

In the modification illustrated in Fig. 5, the receptacle 1'', the body of which may be 55 of any suitable formation, is provided with a contracted tapered throat 1^a and a flared mouth or rim portion 1^b forming a drip chamber above the throat 1^a. The stopper 11'', which is preferably made of glass, 60 is tapered from its upper to its lower end, whereby the lower end of the stopper may fit within the throat 1^a of the receptacle, the upper end of the stopper forming the neck or spout. The stopper 11' is provided with a lateral opening or port 16'' 65 above the throat 1^a for directing the drippings from the drip chamber back into the body of the receptacle, the tongue 20 of the clip 18 being readily passed through the 70 opening 16'' for securing the clip in place, similar to that above described in connection with Figs. 1 and 2. The other parts illustrated in Fig. 5 are practically the same as illustrated in Figs. 2 and 3, and 75 need not be described in detail.

Having thus described the invention, what is claimed as new is:—

In a device of the character described, a receptacle, a spout therefor, there being a 80 drip chamber between the rim of the receptacle and the spout, the spout having a lateral opening leading from the drip chamber to the interior of the receptacle, a clip including a body portion resting snugly 85 against the outer side of the spout above the said opening, the body portion of the clip having an upper flexible tongue bent back over the upper end of the spout and a lower flexible tongue projecting through 90 the said opening and bent upwardly, and a cap hinged to the body portion of the clip and seatable on the upper end of the spout.

In testimony that I claim the foregoing as my own, I have hereto affixed my signature in the presence of two witnesses. 95

JAMES SAMUEL JONES.
